(57) **CLAIM**

The ornamental design for a needle unit for automatic injecting device, as shown and described.

DESCRIPTION

FIG. 1 is a front top right perspective view of the needle unit for automatic injecting device, wherein needles are shown in an inserted position;

FIG. 2 is a front elevational view of the needle unit for automatic injecting device of FIG. 1;

FIG. 3 is a rear elevational view of the needle unit for automatic injecting device of FIG. 1;

FIG. 4 is a left side elevational view of the needle unit for automatic injecting device of FIG. 1;

FIG. 5 is a right side elevational view of the needle unit for automatic injecting device of FIG. 1;

FIG. 6 is a top plan view of the needle unit for automatic injecting device of FIG. 1;

FIG. 7 is a bottom plan view of the needle unit for automatic injecting device of FIG. 1;

FIG. 8 is a front top right perspective view of the needle unit for automatic injecting device of FIG. 1, wherein the needles are shown in a protruding position;

FIG. 9 is a front elevational view of the needle unit for automatic injecting device of FIG. 8;

FIG. 10 is a rear elevational view of the needle unit for automatic injecting device of FIG. 8;

FIG. 11 is a left side elevational view of the needle unit for automatic injecting device of FIG. 8;

FIG. 12 is a right side elevational view of the needle unit for automatic injecting device of FIG. 8;

FIG. 13 is a top plan view of the needle unit for automatic injecting device of FIG. 8;

FIG. 14 is a bottom plan view of the needle unit for automatic injecting device of FIG. 8;

FIG. 15 is a front top right perspective view of the needle unit for automatic injecting device of FIG. 1, shown mounted on an automatic injecting device; and,

FIG. 16 is a front top right perspective view of the needle unit for automatic injecting device of FIG. 8, shown mounted on an automatic injecting device.

The broken lines shown represent unclaimed subject matter and form no part of the claimed design. The dash-dot lines shown are boundary lines and form no part of the claimed design.

1 Claim, 16 Drawing Sheets
